CATALYTIC CRACKING FEED STOCK PREPARATION

Sewall J. Oerling, New Orleans, La., assignor to Shell Oil Company, New York, N.Y., a corporation of Delaware

Filed June 16, 1958, Ser. No. 742,219

5 Claims. (Cl. 208—361)

This invention relates to the separation and recovery of a flashed distillate suitable as a feed stock for catalytic cracking from a petroleum residue by vacuum flashing.

The quantity of petroleum products produced by catalytic cracking has greatly increased over the years, and to satisfy the increasing demand, various stocks, some of which were formerly considered unacceptable, have been employed as feed to the cracking units. Petroleum residue stocks have become widely used for this purpose, and in order to reduce their pitch content (a cause of catalyst fouling) various processes have been used, among which are propane deasphalting, delayed coking and vacuum flashing.

In the latter process the petroleum residue is heated in a furnace to achieve partial vaporization and the mixture of vapor and unvaporized liquid (pitch) is passed to a flash tower maintained under vacuum. Here the overhead vapor removed from the tower condenses to give a flashed distillate product. The process is relatively straight forward providing the catalytic cracking feed stock demand can be fulfilled with a shallow flash. Difficulties arise, however, where a deep flash is resorted to to increase the quantity of the catalytic cracking feed stock since the danger of a too high carry over of the pitch then becomes imminent. Even quite small amounts of the pitch residue entrained in the flashed vapors will severely degrade the quality of the flashed distillate as a catalytic cracking feed stock.

To lessen the pitch carry over, the partially vaporized petroleum residue stream from the furnace is commonly admitted to a centrifugal separation zone and there most of the pitch readily separates to provide a relatively clean superheated vapor. However, because of the low pitch specification of a good catalytic cracking feed stock, it has been found necessary generally to reduce still further the pitch content of the vapor from the centrifugal separation zone. This further reduction of pitch content may be accomplished by passage of the vapor through a de-entraining zone provided with suitable baffling, such as a foraminous mist coalescer or grid trays or both which serves to knock out most of the remaining pitch. But in such an operation, it has developed that the baffling must be maintained wet in order to prevent a build up of the pitch which would otherwise in time cause clogging. Conventionally, this has been achieved by refluxing a sizeable portion of the flashed distillate product to the de-entraining zone where it wets the baffling, continuously washing the mist coalescer or other baffling free of the heavy pitch material collecting thereon. The difficulty that has been encountered in wetting the foraminous mist coalescer type baffling has been described in Hausch, U.S. 2,809,923. There it is pointed out that in order to wet satisfactorily the coalescer mat it proved desirable to dispose the reflux spray up stream of the mat within the de-entraining zone. Placement of the reflux spray immediately down stream of the mat was found inadequate as evidenced by the clogging of the mat in time. It appears that the rising vapor from the

underlying centrifugal separation zone is under non-equilibrium conditions and possesses a significant superheat. This excessive heat, it is theorized, vaporizes a large portion of the reflux stream making it unavailable for the wash purpose. It is thought, therefore, the placement of the Hausch reflux spray up stream of the coalescer mat assures wetting of the mat since the spray in this position can first dissipate a significant portion of the superheat before the vapor contacts the wetted mat.

5 With this superheat dissipation, there is less likely to occur a "distilling" of the liquid in the mat; thus, permitting the mat to remain wet, affording the fluid, coalesced material collecting on the mat an opportunity to drain therefrom, avoiding clogging. It appears that the reflux distillate serves principally in two roles, namely, to dissipate superheat and to wet the surface of the baffling. The total quantity of refluxed flashed distillate required can place a considerable burden on the condensing system and the furnace, particularly where the throughput of a vacuum flasher is increased beyond design.

10

15 It is an object of this invention to provide an improved process permitting an increase in throughput of an existing vacuum flasher bottlenecked by either the low reflux make capacity of its condensing system or possibly by its limited furnace design.

20 It is still another object of this invention to provide a process for the vacuum flashing of a residual feed stock requiring a system having a lower furnace capacity and condensing capacity than formerly possible for the same throughput.

25 Another object of this invention is to provide a more economical vacuum flashing process and a process with reduced incipient cracking. These and other objects will become more apparent with a reading of the following detailed description of the invention when taken in conjunction with the drawings wherein:

30 Fig. I is a schematic representation of a presently preferred system for the practice of the process; and

35 Fig. II is a flow diagram of another embodiment of the process of the invention.

40 It has now been discovered that in a vacuum flashing process of the type employing a centrifugal separation zone (cyclone) to separate unvaporized pitch from vapor and wherein superheat vapor from the centrifugal zone passes through a de-entraining zone provided with suitable deentrainment baffling which is maintained wet by a reflux liquid, that the amount of reflux prepared from the condensate of the vapor may be decreased by employing for a portion of the reflux, a pitch containing petroleum residue which is introduced as a spray into the de-entrainment zone up stream of the mentioned baffling. Preferably and conveniently, the pitch containing petroleum residue spray and the petroleum residue serving as feed to the vaporizing furnace are of the same composition. Surprisingly, the use of this pitch containing material substituted in part for the condensate reflux does not objectionably increase the pitch content of the overhead product from the de-entraining zone. It is believed that the pitch containing residue petroleum spray dissipates or extracts a significant portion of the superheat of the vapor rising from the underlying cyclone and thus, is able to effectively replace a portion of the normal condensate reflux thereby reducing the expense of condensation, and at the same time achieving a reduction in fuel costs to the extent of the petroleum residue by-passing the furnace. The superheat vaporizes a large portion of the non-pitch content of spray, leaving its pitch content in a liquid form. Depending on the size of the spray droplets and the velocity of the vapor the unvaporized pitch of the spray either drops to the bottom of the de-entraining zone or is moved along with the pitch of the rising vapors into contact with the de-entrainment baffling. In order

to reduce the pitch load collecting on the baffling, it may be desirable to employ a rather coarse spray to increase the amount of pitch falling directly to the cyclone bottom. Large size spray particles also further the removal of the pitch out of the rising vapors by direct washing. Another advantage attending the process is the reduction in the amount of incipient cracking over that normally experienced in vacuum flashing. This advantage will be proportional to the relative magnitudes of the furnace feed per se and the stream of petroleum residue by-passing the furnace.

In the preferred arrangement as illustrated in Fig. 1 and described in the example below, the lower spray (preferably a portion of the feed) is sprayed downwardly into the rising vapors from the centrifugal separation zone, with no grid tray or mist coalescer placed below it. The upper spray which is supplied with a product distillate (condensate) reflux is spaced above this lower spray with one or perhaps more grid trays interposed therebetween and preferably immediately below a foraminous mist coalescer. The grid tray and the coalescer are maintained in a wet condition to avoid clogging. It is believed that the lower spray dissipates a significant portion of the superheat of the rising vapor before it contacts the wetted baffling. By this arrangement, it will be seen that the amount of reflux distillate or condensate required is reduced to the extent that the feed reflux (the lower spray) dissipates superheat. The feed reflux should not be substituted completely for the condensate reflux because the pitch content of the overhead vapor stream can then be expected to become objectionably large. Preferably, the lower reflux spray of the pitch containing petroleum residue is used in an amount that will dissipate at least a significant portion of the superheat of the vapor before it contacts the de-entrainment surface, but in an amount that will not increase the pitch content of the vapor stream beyond the normally tolerated in an acceptable catalytic cracking feed stock. Generally speaking, 0.5 to 1.0 volumes (barrels) of the lower reflux are employed for a volume of the upper reflux. It is normal practice in conventional vacuum flashing systems and in the process of the invention, to use in the range of 0.07 to 0.12 barrel of reflux (the two sprays combined in the instance of invention) per barrel of the petroleum residue throughout.

Petroleum residues generally of the type employed for the preparation of a catalytic cracking feed stock are suitable both as furnace feed and as residue spray to the de-training zone. Both short and long residues of varying pitch content may be employed.

The conditions of temperature and subatmospheric pressure used in the process of the invention are substantially those conventionally employed for vacuum flashing generally. The portion of the feed diverted around the furnace for use as a lower spray to the de-entraining zone is preferably introduced at a relatively low temperature to permit the greater adsorption of superheat per volume flow of the feed reflux. However, if the long residue or other residual feed is available at a higher temperature, it may be used without cooling.

The practice of the invention is not limited to the preferred scheme as illustrated in Fig. 1 but may be utilized in connection with other baffling and spray arrangement to achieve a dissipation of at least a significant portion of the vapors superheated prior to its contacting of the condensate reflux wetted portion of the baffling. An alternative embodiment is illustrated in Fig. II and there it will be seen there is no baffling interposed between the two sprays. The lower feed spray contacts the hot, superheated vapor exiting from the underlying centrifugal separation zone, dissipating at least a considerable portion of the excess heat prior to the vapors contacting of the foraminous mist coalescer type baffling which is placed in that embodiment immediately above the condensate reflux spray. The upper spray maintains the

baffling in a wet condition which assures that the pitch collecting thereon will continuously drop off, falling to the bottom of the de-entraining zone from whence it is removed. In the practice of this embodiment it is recommended that a large size particle spray may be employed for the lower spray.

Conceivably, the lower feed spray may be placed between, say the bottom two of the grid trays in the instances where multiple trays are utilized between the two sprays. However, if this is done, it is essential that the vapor flow be uniformly distributed over the cross section of the de-entraining zone before contacting the lowermost grid tray. Otherwise, there will be a liquid build up and a dumping of the liquid on the lowermost tray, resulting in a wide variation in pressure drop across that tray and a surging of the bottoms level. To lessen the likelihood of this occurrence, in the preferred embodiment of Figure 1, the spray is placed below the single tray. Normally, only a single tray need be employed between the two sprays.

With reference to Fig. 1 a reduced crude stream flowing through a line 10 enters a furnace 11 where the reduced crude is heated to a conventional elevated temperature in the range of 775-825° F. to vaporize substantially all of the stream, excepting the heavy pitch portion. The vaporized stream moves through a transfer line 12 to a tangential inlet of a cyclone separator 13 which forms the lower portion of an integrated vacuum flasher 15. The vacuum flasher is generally of a conventional design with the centrifugal separation zone containing a centrally disposed stand pipe 17 within the cyclone. The swirling vapor stream being blocked from passing upwardly by a collar 19 which encompasses the stand pipe, passes downwardly along the outside of the stand pipe and then upwardly through the stand pipe into an overlying de-entraining zone 21. The upper, open end of the stand pipe has a deflector 14 spaced immediately above it. The inverted show off device 16 (around the top of the stand pipe) is designed to direct any pitch that may be crawling upwardly of the interior wall of the stand pipe into the annular removal trough defined by the collar 19. Most of the liquid pitch carried by the vapor stream drops out and collects in the bottom reservoir 23 of the cyclone separator. The material collecting there is removed through an exit line 25. In Fig. 1, the rising vapors first encounters a spray of the pitch containing feed from nozzle 27. The nozzle is supplied with a portion of the feed diverted around the furnace via a line 29 which in turn connects into the feed supply line 10. Immediately downstream of the feed spray nozzle, there is placed a single grid type tray 22 of conventional design. The tray is maintained wet and assists in reducing the pitch content of the vapor stream passing through the de-entraining zone. Above the grid tray there is disposed within the de-entraining zone a second set of spray nozzles 28. This set of nozzles, similar to the one below, is conventional in design and is arranged over the cross section of the tower so that substantially all of the rising vapors are covered by the spray. The liquid for the nozzles of this top spray is supplied via a line 31 which connects to the liquid outlet of a vapor-liquid separator 33 through a line 35.

There is placed in the upper portion of the de-entraining zone immediately above the upper spray a foraminous mist coalescer 30 of conventional design. A preferred coalescer takes the form of a mat of tangle wire several inches thick, such as, for example, the York mat manufactured by Otto H. York, Inc., West Orange, New Jersey, or the Metex mat manufactured by the Metal Textile Corporation, Roselle, New Jersey. These mats have an open volume upwards of 85% and a density between 3-15 pounds per cubic foot depending on the degree of wire compression. Another suitable coalescer is the Schuyler mat. Such mats present a very small pressure drop.

The coalescer mat 30 substantially completes the removal of the pitch entrained in the rising vapor and the vapor passes therethrough into the head space of the de-entraining zone, leaving through a removal line 37 which opens into a partial condenser 39, cooled by water, where the heavier components of the vapor stream are condensed. The vapor stream in an alternative may be cooled by the feed prior to its passage to the furnace 11. The remaining vapor and condensate flow to the separator 33 and there the condensate (heavy flashed distillate) collects in the bottom of the vessel and is removed through the previously mentioned line 35. A portion of the heavy flashed distillate is returned as reflux via line 31 and the remainder is transferred in a line 41 to catalytic cracking.

The vapors collecting in the head space of the separator 33 leave through a line 43 to a second condenser 45 where the rest of the petroleum residue vapors are condensed and subsequently separated in a vessel 47. The light condensate is removed from this latter vessel via a line 49 and may be transferred to the catalytic cracking unit or other usage. A vacuum source is connected to this latter separation vessel 47 via a line 50.

The pitch dropping from the de-entraining baffling collects in the annular removal trough (which has at its bottom the collar 19) of the de-entraining zone. From there the fluid pitch flows through a run back line 52 to the pitch reservoir 23 placed below the cyclone.

In Fig. 2 the reduced crude enters a furnace 60 via a line 61. The vaporized reduced crude exits from the furnace through a transfer line 61 and is introduced to a cyclone 64 below a vacuum distillation unit 65. The entrained pitch drops out of the swirling vapor and falls to the top tray of a steam stripping tower 66, disposed directly beneath the cyclone separator. Superheated vapor of low pitch content leaves the cyclone through its centrally disposed stand pipe 67, passing upwardly into the overlying de-entraining zone 69 of the vacuum flasher. Here the vapor is first contacted by a spray of the feed from a first nozzle arrangement 71. The set of nozzles is in the lower portion of the de-entraining zone spaced some distance up stream of a second set 73 of similar nozzles. Preferably, the lower nozzles are designed to provide a spray with larger drop size than the upper spray. The feed for the lower spray 71 is supplied by a line 75 which branches off of the reduced crude feed line 61, a short distance preceding the furnace. The lower spray extracts much of the superheat of the rising vapor which continues upwardly through the de-entraining zone into contact with the aforementioned second spray. The second spray is a heavy flashed distillate (condensate) which is recovered from the vapor product leaving the de-entraining zone. The second spray wets a coalescer mat 77 which is placed immediately above the second nozzle set 73. The vapor leaves the vacuum flasher through a line 79 into a partial condenser 80 where the heavy flashed distillate condenses and is subsequently separated from the remaining vapor in a separating vessel 83. The heavy flashed distillate is removed from the latter vessel through a line 85 and returned in part through a line 87 as the reflux to the upper spray nozzles 73. The rest of the heavy flashed distillate condensate is passed to the catalytic cracking unit in a line 89. Vapor from the separating vessel 83 leaves in a conduit 90 which opens into a second condenser 91 where the remaining petroleum vapor is condensed. The light flashed distillate is removed as a liquid through line 93 from the bottom of a separating vessel 94. The head space of this latter vessel connects through a line 95 to a vacuum source.

The pitch collecting on the coalescer mat falls to a pitch removal annular trough 96 and from there passes through a run-back line 97 into the steam distillation tower 66. Steam enters via a line 101 and a nozzle 98 into the lower portion of the distillation tower to strip the lighter material from the heavy pitch. The pitch collects

in a sump 99 and is removed therefrom through a line 100.

This second embodiment of Fig. 2, since it contains less de-entrainment surface than that of Fig. 1, is less suitable to the processing of reduced crudes of relatively high pitch content and is accordingly best used in the processing of low pitch content residues and in relatively low throughputs.

EXAMPLE

10 Eight evaluation tests were conducted at varying transfer temperatures, amounts and types of reflux to the upper and lower sprays in a pitch de-entraining system of the type illustrated in Fig. 1. The first three tests (runs 1-3) were conducted with varying amounts of a heavy flashed 15 distillate to the lower and upper reflux sprays 27, 28 respectively. The heavy flashed distillate is the condensate collecting in the bottom of the separating vessel 33. These first three tests typify conventional practice. The following three tests (runs 4-6) employ varying 20 amounts of the heavy flashed distillate refluxed to the upper reflux spray with differing amounts of a straight run residue supplied to the lower reflux spray 27. The feed to the furnace 11 is of the same composition as this 25 lower reflux spray. The three runs 4-6 represent the process of the invention.

The conditions and results of the several runs are reported in the table below. In all of the first six runs the furnace transfer temperature was kept constant. The entry entitled "Feed" is the feed to the furnace and the "H.F.D. reflux upper" and "H.F.D. reflux lower" are the volume flows of the heavy flashed distillate, respectively, to the upper and lower sprays 28, 27 expressed in barrels per day (b./d.). The volume of vapor passing overhead from the flasher through the line 37 appears under the item "Overhead" and is expressed as a total condensate in b./d. In the instance of runs 4-6, the entry "S.R.R. reflux lower" is a volume account in barrels per day of the straight run residue supplied to the lower reflux spray. The "Pitch" entry represents the amount of pitch removed in barrels per day through the bottoms line 25. The item entitled "Pitch percent (based chg.)" is a percentage ratio of the pitch in the feed entering the furnace 11. The item "Pitch ent." is an expression of percentage ratio by weight of the pitch entrained in the vapor stream 37. The "Transfer temperature" item is the temperature of the heated residual stream leaving the furnace while the "Vaporline" entry is the temperature of the vapor leaving the de-entraining zone in line 37. The pressure of the flasher is taken at the top of the de-entraining zone, 35 above the coalescer mat.

The runs within the following pairs are best compared, 70 namely, runs 3 and 4, runs 2 and 5 and runs 1 and 6. It will be seen that the individual runs of the foregoing pairs have the same volume flows to their respective upper and lower trays. The test runs 4-6 which employ the straight run residue as the lower reflux, gave lower pitch yields than the control runs 1-3 in which the heavy

flashed distillate was supplied as the lower reflux spray. The several tests and control runs have the same order of pitch entrainment, indicating there was no appreciable change in the flashed distillate quality as measured by pitch entrainment. There is a significant increased throughput for the test runs 4-6 at the same furnace transfer temperature. Run 6 gave the lowest overall pitch production while using 2000 b./d. of the heavy flashed distillate to the upper spray and 1000 b./d. of straight run residue to the lower spray. Runs 7 and 8 were conducted to determine the effect of increased furnace temperature on pitch yields. It will be seen that at the higher transfer temperature there is a reduction of 1.77% in pitch production.

I claim as my invention:

1. In a vacuum flashing process for the preparation of a catalytic cracking feed stock of an acceptable low pitch content from a pitch-containing petroleum residue, wherein in the process involves heating the residue in a furnace to provide an unvaporized pitch entrained in a vapor, passing the vapor through a centrifugal separation zone and there separating superheated vapor from most of the pitch, subsequently removing the superheated vapor to a de-entraining zone and there passing the vapor upwardly through the zone into contact with a de-entrainment surface disposed therein and wetted by a reflux liquid constituting a part of the product condensate of the vapor leaving said de-entrainment zone to lower still further the pitch content of the vapor by retention of pitch on said de-entrainment surface, the improvement comprising contacting the vapor upstream of the wetted de-entrainment surface and beyond the centrifugal separation zone with a pitch containing petroleum residue spray introduced in an amount effective to dissipate at least a significant portion of the superheat of the vapor before it contacts said de-entrainment surface, thus reducing the amount of the product vapor condensate refluxed to the de-entraining zone and permitting a reduction in furnace fuel cost.
2. A process in accordance with claim 1, wherein the pitch containing petroleum residue spray and the petroleum residue to the furnace are of the same composition.
3. In a vacuum flashing process for the preparation of a catalytic cracking feed stock from a petroleum residue,

wherein the process involves heating the residue in a furnace to provide an unvaporized pitch entrained in a vapor, passing the vapor to a centrifugal separation zone and there separating superheated vapor from most of the pitch, subsequently removing the superheated vapor to a de-entraining zone and there passing the vapor upwardly through the zone into contact with a de-entrainment surface disposed therein and wetted by a reflux liquid prepared from the product vapor condensate leaving said de-entrainment zone to lower still further the pitch content of the vapor by retention of pitch on said de-entrainment surface, the improvement comprising spraying the superheated vapor from the centrifugal separation zone with a relatively low temperature, pitch-containing petroleum

5. 10. 15. 20. 25.
  10. 15. 20. 25.
  15. 20. 25.
  20. 25.
  - 25.
- residue within the de-entraining zone upstream of said de-entrainment surface to dissipate a substantial portion of the superheat before the vapor contacts said de-entrainment surface, said de-entrainment surface comprising a foraminous mist coalescer which is wetted by a spray of the product reflux introduced to the de-entraining zone immediately upstream of the coalescer and beyond the place of spraying of the pitch-containing petroleum residue, thus reducing the amount of the product vapor condensate refluxed to the de-entraining zone and permitting a reduction in furnace fuel cost.

4. A process in accordance with claim 3 wherein the pitch-containing petroleum residue spray and the petroleum residue to the furnace are of the same composition, and about one volume of the petroleum residue spray is employed for a volume of the vapor reflux spray.

5. A process in accordance with claim 3 wherein the de-entrainment surface comprises in addition to the foraminous coalescer, at least one grid plate maintained in a wetted condition and placed between the two sprays to assist in the displacement of the pitch from the vapor.
